[57] CLAIM

The ornamental design for a vertical fluorescence microscope attachment, as shown and described.

DESCRIPTION

FIG. 1 is a front, left side perspective view of the vertical fluorescence microscope attachment showing my new design;

FIG. 2 is a left side elevational view thereof;

FIG. 3 is a top plan view thereof;

FIG. 4 is a bottom plan view thereof;

FIG. 5 is a front elevational view thereof; and

FIG. 6 is a rear elevational view thereof.

FIG. 1

FIG. 2

FIG. 3

FIG. 4

FIG. 5

FIG. 6
